(57) **CLAIM**

We claim the ornamental design for a solar-powered outdoor light, as shown and described.

DESCRIPTION

FIG. 1 is a perspective view of a solar-powered outdoor light showing the new design;

FIG. 2 is a right side elevational view thereof;

FIG. 3 is a left side elevational view thereof;

FIG. 4 is a front elevational view thereof; the rear elevational view being a mirror image thereof;

FIG. 5 is a top plan view thereof; and,

FIG. 6 is a bottom plan view thereof.

1 Claim, 4 Drawing Sheets**FIG. 1**

FIG. 2**FIG. 3**

FIG. 4

FIG. 5**FIG. 6**
